UNITED STATES PATENT OFFICE.

AUGUST B. HOOK, OF NEW YORK, N. Y., ASSIGNOR TO ROSENSTEIN BROS. & HOOK, OF NEW YORK, N. Y., A CORPORATION OF NEW JERSEY.

DESIGN FOR A FABRIC.

Application filed April 11, 1929. Serial No. 30,851. Term of patent 3½ years.

To all whom it may concern:

Be it known that I, AUGUST B. HOOK, a citizen of the United States, residing at New York, in the county of New York and State of New York, have invented a new, original, and ornamental Design for a Fabric, of which the following is a specification, reference being had to the accompanying drawing, forming part hereof, showing a fragment of the fabric bearing the design, the remaining portion as appearing in dot and dash lines being ornamented in the same manner as the part in full lines.

I claim:

The ornamental design for a fabric, as shown and described.

AUGUST B. HOOK.
